UNITED STATES PATENT OFFICE.

FRANK X. BIBEAULT, OF WATERBURY, CONNECTICUT.

HEEL.

1,159,738.

Specification of Letters Patent.

Patented Nov. 9, 1915.

Application filed July 2, 1915. Serial No. 37,718.

To all whom it may concern:

Be it known that I, FRANK X. BIBEAULT, a citizen of the United States, residing at Waterbury, in the county of New Haven and State of Connecticut, have invented a new and useful Improvement in Heels; and I do hereby declare the following, when taken in connection with the accompanying drawings and the characters of reference 10 marked thereon, to be a full, clear, and exact description of the same, and which said drawings constitute part of this application, and represent, in—

Figure 1 an outer face view of a rubber heel constructed in accordance with my invention. Fig. 2 a view in vertical section. Fig. 3 an outer face view of the sections slightly separated. Fig. 4 an inner face view. Fig. 5 an outer face view of a heel 20 embodying my invention and comprising three sections. Fig. 6 illustrates means for applying the sections of a heel.

This invention relates to an improvement in heels for boots and shoes, and particularly 25 to rubber heels.

As is well known some persons wear the heels at the back; some at one side, and some at the other.

The object of this invention is to construct a rubber heel in sections either of 30 which is removable without disturbing the others, and provide means whereby these sections are suitably supported and secured in place; and the invention consists in a 35 rubber heel having certain details of construction as will be hereinafter described and particularly recited in the claims.

In carrying out my invention as shown in Figs. 1, 2, 3 and 4 of the drawings, I 40 form the heel in four sections comprising a front 2, back 3, and sides 4 and 5. These sections are triangular in general form, and the abutting edges of each part are beveled to form V-shaped channels 6 which meet at 45 substantially the center of the heel. Preferably and as shown in Figs. 1 and 3 of the drawings, each section will also be provided with a transverse V-shaped groove 7. The inner faces of these sections are in- 50 wardly curved from the outer edges to triangular blocks 8, 9, 10 and 11 forming a chamber 20 in each section, as shown in

Fig. 2 of the drawings. These blocks when the edges of the sections are abutted, form a rectangular support at the center of the heel, 55 permitting the edges of the sections to closely fit the edge of the heel to which the sections are applied. The chambers 20 form vacuum chambers which assist in holding the edges of the sections in place. 60

Instead of forming the heel from four sections, it may be formed from three sections 17, 18 and 19, as indicated in Fig. 5 of the drawings, in which case the support at the center will be triangular instead of rectangular. As shown in dotted lines in Fig. 4, the edges of the blocks 8, 9, 10 and 11 might be curved so as to form a round plug or support at the center instead of a rectangular or triangular support. As a means 65 for securing the sections to the heel, I preferably employ nails 12 as shown in Fig. 6 of the drawings, the main portion of the nail, being driven into a leather heel 14, while the outer end projects beyond the face 75 of the leather heel and is provided with a series of heads 15 one above the other, the heads being preferably rounded and the sections are each provided with holes 16 in line with the nails 12 so that the sections can 80 be pressed down over the heads of the nails and thereby secured in place. With heels thus constructed, if the back section wears down, it can be removed and a new section inserted; or if either the side sections wear 85 down they can be replaced by new ones; or the outside section of the heel of one shoe can be interchanged with the inside section of the other shoe so as to produce a practically new wearing surface for each heel 90 without the use of new parts. The beveling of the edges of the sections assists in bringing the parts into line with each other and tend to even up or level the section when a new one replaces one worn down. Beveling 95 at the edges and the transverse grooves also tend to prevent slipping, although as indicated in Fig. 5 of the drawings, the transverse grooves may be omitted, if desired.

I claim:—

1. A rubber heel comprising a plurality of angular sections the inner faces of which are partially recessed leaving an unreduced portion at the inner end of each section

which unreduced portions together form a central support.

2. A rubber heel comprising a series of sections the inner faces of which are partially recessed leaving an unreduced portion at the inner end of each section, which portions together form a central support,

the abutting outer edges of each section being beveled, whereby a groove is formed between the sections.

FRANK X. BIBEAULT.
